CLAIM

The ornamental design for a fluid-containment wall segment, as shown and described.

DESCRIPTION

FIG. 1 is a front perspective view of one embodiment of a wall segment, showing our new design;

FIG. 2 is a top plan view;

FIG. 3 is a front elevational view;

FIG. 4 is a left side elevational view;

FIG. 5 is a right side elevational view;

FIG. 6 is a rear elevational view;

FIG. 7 is a bottom plan view; and,

FIG. 8 is a front perspective view of another embodiment of a wall segment of our invention, which is a mirror image of the embodiment shown in FIGS. 1-7.
